UNITED STATES PATENT OFFICE

155,962

DESIGN FOR AN ELECTRIC HEATER

Guy H. Allgeyer, Toledo, Ohio, assignor to The Swartzbaugh Manufacturing Company, Toledo, Ohio, a corporation of Ohio

Application December 26, 1947, Serial No. 143,352

Term of patent 14 years

(Cl. D81—10)

To all whom it may concern:

Be it known that I, Guy H. Allgeyer, a citizen of the United States, residing at Toledo, in the county of Lucas and State of Ohio, have invented a new, original, and ornamental Design for an Electric Heater, of which the following is a specification, reference being had to the accompanying drawing, forming a part thereof.

In the drawings:

Figure I is a front perspective view of an electric heater, showing my new design.

Figure II is a fragmentary vertical sectional view taken substantially on the line II—II of Figure I.

The dominant features of my design reside in the portions shown in full lines.

I claim:

The ornamental design for an electric heater, as shown and described.

GUY H. ALLGEYER.
